UNITED STATES PATENT OFFICE.

WILLIAM HACKLY CHURCH, OF SUPERB, SASKATCHEWAN, CANADA.

SHOCKING-MACHINE.

1,332,104.

Specification of Letters Patent. Patented Feb. 24, 1920.

Application filed April 16, 1918; Serial No. 228,843. Renewed January 7, 1920. Serial No. 350,055.

To all whom it may concern:

Be it known that I, WILLIAM HACKLY CHURCH, of the town of Superb, in the Province of Saskatchewan, Canada, have invented certain new and useful Improvements in Shocking-Machines, of which the following is the specification.

The invention relates to improvements in shocking machines and particularly an improvement in my previous grain shocker which is fully disclosed and described in U. S. Patent No. 1,240,823 and dated the 25th day of September, 1917, and the principal objects of the invention are to provide, in a machine of the type disclosed, a means for steadyng the stook as it is being dumped and after dumping and further to provide a means for holding the stook in the basket while being dumped and for automatically releasing it to dump at the proper instant.

With the above objects in view the invention consists essentially in a pair of automatically controlled pressure arms carried by the sides of the basket and a pair of automatically controlled steadyng fingers mounted on the shocker frame and adapted to pass in behind the stook and go back with it to steady the same after it has been upended and dumped, the parts being arranged and constructed as hereinafter more particularly described and later pointed out in the appended claims, reference being had to the accompanying drawings in which:

Figure 1 represents a plan view of the shocking machine.

Fig. 2 represents a side view of the same.

Fig. 3 represents an enlarged detailed side view of the steadyng fingers and parts immediately associated therewith.

Fig. 4 represents a plan view of the parts appearing in Fig. 3.

Fig. 5 represents a vertical sectional view transversely through a part of the shocker frame, the section being taken in the plane denoted by the line X—X' Fig. 3 and looking in the direction indicated by the applied arrow.

Fig. 6 represents a sectional view similar to that appearing in Fig. 5 but looking in the opposite direction.

Fig. 7 represents an enlarged detailed vertical sectional view through the bearing for the basket shaft at the outer side of the frame.

Fig. 8 represents a vertical sectional view through the basket and frame showing the rods controlling the basket arms.

Fig. 9 represents an enlarged detailed side view of the outer basket arm.

Fig. 10 represents an enlarged detailed side view of the inner basket arm.

Fig. 11 represents a perspective view of one end of the guide track for the fingers.

In the drawings like characters of reference indicate corresponding parts in the several figures.

In order that this invention may be better understood I will refer to parts of my former machine as disclosed in the patent aforesaid but will not give a detailed description of such parts as they are fully disclosed and described in the former patent.

The stooker frame, indicated generally by the reference letter E, supports rotatably the inner end of the basket shaft 11 provided intermediate of its ends with a curvilinear portion 12 adapted to carry the basket collector F. The inner side of the basket frame is suitably supported from the frame of the binder, (not shown) such being omitted in the present disclosure and the outer side is supported by a ground wheel 14 rotatably mounted on the outer end of the shaft 11.

A crank member 15 is fixed to the shaft 11 and carries an angular lever 16 pivotally mounted thereon, the inner end of which is substantially curvilinear as shown at 17 and is adapted to engage with a pin 18, thereby limiting the outer motion of the lever which is adapted to be pressed inwardly to engage with the spokes of the wheel 14.

The lever 16 is provided with a projection 27 designed to be engaged by a spring 28 adapted to hold the said lever normally disengaged from the spokes of the wheel and the said lever is adapted to be moved into engagement with the spokes through the medium of the bell crank 29 pivotally mounted on the frame E and operatively connected by the link 30 with the bell crank 31 mount-

ed on the frame. A flexible member, such as a cable 32, is connected to the bell crank 31 and passes to a convenient location adjacent the driver on the binder.

- 5 From this arrangement it will be seen that on the pulling of the cable the member 16 will be engaged with the spokes of the wheel and that the crank member 15 will be caused to rotate and in rotating will turn 10 the shaft 11 and consequently the basket. Associated with the front end of the basket I have provided a door or butting plate J which is suspended from the frame in the same manner as disclosed in my former 15 patent and is caused to be withdrawn and as it forms no part of the present invention is not further described.

The above parts form no part of the present invention which comprises in reality 20 pressure arms carried by the basket and steadyng fingers carried by the frame and associated with the basket. These parts are now described in detail.

At diametrically opposite points and rear- 25 wardly of the basket I locate a pair of horizontally disposed operating shafts *a* and *b* which are rotatably mounted in suitable bearings *c* secured to the edges of the basket. The forward ends of these shafts 30 are fitted with outwardly extending cranks *a'* and *b'* and the rear end of the shaft *b* is supplied with a single arm *d* which is permanently secured to the shaft and is held normally open in respect to the basket 35 by means of a coiled spring *d'* mounted on the shaft and having one end fastened to the basket as indicated at *d*^x and the other end projecting and coiled around the arm as indicated at *d*^z.

40 The rear end of the shaft *a* is supplied with a U-shaped arm *e* which is permanently secured to the shaft and is held normally in the open position in respect to the basket by means of a coiled spring *e'* mounted on 45 the shaft and having one end fastened to the basket as indicated at *e*^x and the other end extending and looped around the arm as indicated at *e*^z.

These springs normally hold the arms in 50 the upper position so that they do not interfere with the passing of the sheaves into the basket from above.

In order to close the arms when the basket is dumped by the turning of the shaft 11 55 I provide a pair of striker plates *f* and *g* which are permanently secured to the shocker frame in a location in advance of the shaft 11 and provided each with a downwardly bent and rearwardly curving guide *f'* and *g'*, the guides being arranged concentric to the shaft and terminating slightly in advance of a vertical line dropped from the shaft 11.

60 In considering the action of the arms it will be observed that in the initial turning

of the basket the cranks *a'* and *b'* will strike the plates *f* and *g* (see Figs. 1 and 8) and in the initial turning movement of the basket will be caused to rotate in the direction indicated by the applied arrow Fig. 8 70 thereby causing the rods *a* and *b* to turn in a direction such that the arms *d* and *e* will be both swung inwardly over the sheaves contained in the basket. This action causes the sheaves to be compressed 75 and held tightly within the basket during the dumping action and here it will be observed that as the basket continues to turn the outer ends of the crank ride over the guides and hold the arms closed until the 80 cranks escape over the ends of the guides, which action occurs just prior to the basket being upended. The instant the cranks free the guides the rods are freed and the springs *d'* and *e'* operate to swing the arms back to 85 their original open position.

After the basket has dumped and has been returned to the initial receiving position the cranks are lying on the top side of the plates *f* and *g* and are ready for further action. 90

In order to steady the stock after it has left the basket I provide steadyng fingers which are automatically controlled to pass in, in front of the stock and remain with it as the shocker advances, the fingers actually 95 being timed to pass backwardly at the same speed the grain stoker advances so that their movement in respect to the ground is relatively zero.

These fingers have herein been shown as 100 positioned at the outer side of the basket but in this connection I wish it to be understood that they could be applied at both sides of the basket if occasion demand.

The inner beam *E'* at the outer side of 105 the shocking machine is fitted with a bearing *E*^z which receives a sleeve *h* mounted on the shaft 11 and on the sleeve I mount inner and outer chain wheels *j* and *k*, the outer one of which is secured by a pin *i* to the shaft and the inner one of which is mounted freely on the inner end of the sleeve.

Toward the rear end of the beam *E'* I provide a bearing *l* which receives rotatably 115 a short shaft *l'* on which I mount a pair of chain wheels *m* and *n*, which chain wheels are connected by means of inner and outer chains *o* and *o'* with the chain wheels *j* and *k*.

From this arrangement it will be seen that when the shaft 11 turns the chain *o'* rotates the chain *o*. The chain wheels are arranged in the manner shown to allow of varying the speed at which the inner chain 125 wheel travels, this being readily accomplished by varying the size of the chain wheel *n* which drives the chain wheel *j*. The chain *o* is fitted with two special links indicated at *p* and *p'*, such special links be- 130

ing provided with opposing lugs p^x which form bearings for pivot pins q located at the ends of the steadyng fingers r and s . These steadyng fingers are sufficiently long so that when extended crosswise of the basket they pass practically across the same and they are arched slightly from end to end so as to pass around the front of the stook when the fingers are in use.

10 Further the special links carrying the fingers are introduced in the chain at opposite ends thereof so that when one finger is ahead the other is back. Each finger is controlled in a manner shortly to be described so that when going back or rearwardly it takes a horizontal position as best shown in Fig. 1 of the drawings and when going ahead or forwardly it is swung up into the vertical position. In going back it stays with the stook for a short interval after it is dumped steadyng it and then swings up to the vertical position and is reset so that it will subsequently pass in behind a further stook when the same is dumped.

On the fingers and in a location adjoining the pins I mount rollers t and t' which rollers are adapted to ride continuously on a track which controls the movement of the fingers. The track is formed from two bars v and w permanently secured to the frame beam E' and arranged so that the rollers are guided first by the one plate and then by the other. The upper plate has the ends thereof curving gradually inwardly as indicated at v' and v^2 and is provided with a right angled flange v^x , the edge of which gradually vanishes at the ends into the curved ends v' and v^2 .

40 The plate w is supplied with a right angled flange w' which passes the full length of the plate and is concentric at the ends to the shafts 11 and 11'. The curved ends of the plate v pass within the curved flange bearing ends of the plate w and the distance between the two plates at the ends is slightly greater than the diameter of the rollers which allows the rollers to pass between them.

50 The arrangement of the plates in respect to the pivot pins and rollers is such that when the rollers are riding on the flange w the arms are maintained in a horizontal position. This will be best apparent by referring to Figs. 3 and 5 where it will be seen that the lower roller is riding on the flange and the finger is extending horizontally.

As this roller passes from the flange of the plate w to the end v^2 of the plate v the roller is gradually swung by the plate v from the horizontal position to an inclined position, it being in the inclined position (see Fig. 6) when riding on the flange v^x . As it passes along the flange v^x

the roller is maintained in the inclined position until it rides back on to the end v' of the plate where it is again brought to the vertical position and goes back on to the flange w' of the lower plate.

70 In considering this action it will be understood that the chain is moving in the direction indicated by the applied arrow Fig. 3 and is being driven by the shaft 11.

75 In placing the fingers on the chains it is necessary to locate the special links carrying them so that when the basket is in the sheaf receiving or normal position the special links occupy the positions best shown in Fig. 1 of the drawings where it will be observed that the one finger, that r , is horizontal and to the rear and the other finger is inclined and advanced.

80 With these fingers arranged in this way it will be obvious that, when the basket is dumped, the shaft 11 will operate the fingers and that when the basket returns to the initial or set position after dumping the fingers will stop operating for the reason that the shaft 11 is thrown out of commission each time the basket dumps.

85 In the initial movement of the fingers the finger s will be swung down in advance of the upturning end of the basket and in advance of the stook and in passing backwardly will stay with the stook steadyng it until it reaches the position occupied by the finger r in Fig. 1 of the drawings.

90 In this position it will stop as the parts are designed so that when the basket is dumped and returned to the initial position the finger s will have reached the position as shown occupied by the finger r in Fig. 1 of the drawings.

95 During the movement of the finger s as above disclosed the finger r travels a like distance first being turned from the horizontal position as shown in Fig. 1 to the inclined position and then traveling forwardly in the inclined position until it takes the position previously occupied by the finger s .

100 By this arrangement there is one or other of the fingers at all times ready to pass in ahead of the stook each time the basket is dumped and go back with it and steady it on the ground.

105 In the above disclosure it will be easily understood that the details of the track could be readily modified without in the least departing from the spirit of this part 110 of the invention which resides in providing fingers which can pass back with the stook and steady it and arranged so that they can be controlled throughout their entire movements.

115 What I claim as my invention is:—

120 1. In a shocking machine, the combination with a sheaf receiving and shock forming basket and means for dumping the basket to deposit the shock, of means adapt-

ed to swing in in advance of the stook and stay with it to steady the same after dumping.

2. In a shocking machine, the combination

5 with a sheaf receiving and shock forming basket and means for dumping the basket to deposit the shock, of means adapted to pass in in front of the stook as it is dumped from the basket and designed to 10 move backwardly at the same rate as the machine advances thereby steadyng the stook after it is dumped.

15 3. In a shocking machine, the combination with a shocker frame, a sheaf receiving and shock forming basket pivotally mounted on the frame and means for operating the basket to dump the stook, of a steadyng finger carried by the shocker frame and adapted in the dumping operation to pass in in advance of the stook and remain with the stook to steady the same after dumping and as the machine advances.

20 4. In a shocking machine, the combination with a shocker frame, a sheaf receiving and shock forming basket pivotally mounted on the frame and means for operating the basket to dump the stook, of steadyng fingers carried by the machine frame and adapted to alternately pass in 25 behind the successive stooks when the basket is dumped and remain with the stooks steadyng them after dumping.

30 5. In a shocking machine, the combination with a shocker frame, a sheaf receiving and shock forming basket pivotally mounted on the frame and means for operating the basket to dump the stook, of an endless chain mounted on the shocker frame, means for driving the chain during the interval 35 that the basket is dumping and returning to the normal position, a pair of steadyng fingers extending from the chain and a track controlling the fingers such that during 40 the turning of the basket one finger is swung in in front of the stook and stays with it to steady the same as the machine advances and the other finger passes ahead clear of the stook to take the position occupied by the former finger at the beginning 45 of the dumping operation.

50 6. In a shocking machine, the combination with a shocker frame, a sheaf receiving and shock forming basket pivotally mounted on the frame and means for operating the basket to dump the stook, of an 55 endless chain mounted on the shocker frame, means for driving the chain during the interval that the basket is dumping and returning to the normal position, a pair of 60 fingers carried by the chain and disposed at remote locations in the chain and a track for controlling the fingers and constructed such that each time a shock is dumped one of the fingers is brought into engagement 65 with the front side of the stook and remains

with it for an interval of time after dumping and the other finger is reset so as to pass in in front of the subsequently dumped stook and pass back with it.

7. In a shocking machine, the combination 70 with a shocker frame, a sheaf receiving and shock forming basket pivotally mounted on the frame and means for dumping the stook and returning the basket to the initial sheaf receiving position, of an endless chain 75 mounted on the frame to the side of the basket and passing lengthwise of the frame, a pair of steadyng fingers carried by the chain and located at remote points in the chain, means for driving the chain during 80 the interval that the basket is being dumped and returned to the initial position and a stationary track secured to the frame and controlling the movement of the fingers in a manner such that in the dumping of the 85 basket one finger is brought to a position in advance of the stook and passes backwardly with the dumped stook to steady it and the other finger goes ahead clear of the stook and takes the position vacated by the former 90 finger at the beginning of the dumping action.

8. In a shocking machine, the combination 95 with a shocker frame, a basket shaft rotatably mounted on the frame, a sheaf receiving and shock forming basket carried by the shaft and means for turning the shaft one complete revolution to dump the shock and reset the basket, of a rearwardly located short shaft carried by one side of the 100 shocker frame, opposing pairs of chain wheels on the basket shaft and the rear shaft, inner and outer chains operatively mounted on the chain wheels, steadyng fingers carried by the inner chain and located at remote points in the chain and a guide track secured to the frame and controlling the movement of the fingers in a manner such that the fingers are successively swung inwardly to a horizontal position at the forward end of the chain and are successively swung upwardly to an inclined vertical position at the rear end of the chain.

9. In a shocking machine, the combination 115 with a shocker frame, a basket shaft rotatably mounted on the frame, a sheaf receiving and shock forming basket carried by the shaft and means for turning the shaft one complete revolution to dump the shock 120 and reset the basket, of a rearwardly located short shaft mounted on the shocker frame, a pair of chain wheels permanently secured to the basket shaft, an inner chain wheel freely mounted on the basket shaft, an endless inner and outer chains connecting the chain wheels of the basket shaft with those of the short shaft, a pair of pivoted steadyng fingers carried by the inner chain 125 and positioned at remote locations of the lat- 130

ter chain, a roller associated with each finger and a track secured to the shocker frame and controlling the movement of the rollers in a manner such that at the forward end of the inner chain the fingers are swung inwardly to a horizontal position and maintained in the horizontal position in passing backwardly and at the rear end of the inner

chain the fingers are swung to an inclined vertical position and maintained in such position in passing forwardly. 10

Signed at Winnipeg, this 19th day of March, 1918.

WILLIAM HACKLY CHURCH.
